UNITED STATES PATENT OFFICE.

MOSES N. COLE, OF WELLINGTON, KANSAS.

ATTACHMENT FOR COOKING-STOVES.

SPECIFICATION forming part of Letters Patent No. 446,430, dated February 17, 1891.

Application filed June 13, 1890. Serial No. 355,297. (No model.)

To all whom it may concern:

Be it known that I, MOSES N. COLE, a citizen of the United States, residing at Wellington, in the county of Sumner and State of Kansas, have invented a new and useful Attachment for Cooking-Stoves, of which the following is a specification.

This invention has relation to an attachment for grates of cooking-stoves, the objects 10 of the invention being to provide an attachment or supplemental grate designed to be mounted within the grate proper and to be adjusted to or from the bottom of the grate or the top of the stove, whereby the space between the supplemental grate and the top of 15 the stove may be decreased, whereby the burning of such fuel as corn-cobs soaked in oil, and, in fact, other kinds of fuel, is facilitated and a proper amount of heat secured 20 for cooking purposes without an undue expenditure of fuel. In other words, to adapt the stove to perform its proper functions with a lesser amount of fuel than heretofore by the employment of the ordinary grate, and 25 to adapt the supplemental grate to such adjustment as the kind of fuel and the occasion may demand.

With the above objects in view the invention consists in certain features of construction hereinafter specified, and particularly 30 pointed out in the claims.

Referring to the drawings, Figure 1 is a perspective of a stove of ordinary construction provided with a grate attachment constructed 35 in accordance with my invention, the wall of the stove being broken away to expose the same. Fig. 2 is an enlarged detail in perspective of the grate attachment. Figs. 3, 4, and 5 are end elevations illustrating the different 40 adjustments secured by the supporting-blocks. Fig. 6 is a transverse section through the grate and one of the supporting-blocks. Fig. 7 is a detail in perspective of one of the supporting-blocks.

45 Like numerals of reference indicate like parts in all the figures of the drawings.

1 designates a rectangular or oblong frame crossed at intervals by grate-bars 2, the ends of which are upwardly bent, as at 3, at each 50 side of the frame, which series of bent ends are continued at the ends of the frame by means of short vertical bars 4.

The described grate-frame is simply one of the many forms that may be employed, and I do not limit my invention thereto.

55

5 represents supporting-frames, which are of oblong shape, and each has one side provided with a bolt-opening 6 and one end provided with a bolt-opening 7, both of which openings are adapted to register with bolt-openings 8, formed in the end of the grate-frame. Two of these frames are employed, one at each end of the grate-frame, and they are secured in position by means of ordinary bolts 9 or other fastening devices.

65

10 designates a stove of ordinary construction provided at its front with the usual grate 11. The supplemental grate is designed to fit loosely within the fire-box of the stove, and by means of the grate-supporting frame previously described said supplemental grate is supported in an elevated manner within said fire-box, so that it is brought nearer to the top of the stove than the original grate.

60

10 designates a stove of ordinary construction provided at its front with the usual grate 11. The supplemental grate is designed to fit loosely within the fire-box of the stove, and by means of the grate-supporting frame previously described said supplemental grate is supported in an elevated manner within said fire-box, so that it is brought nearer to the top of the stove than the original grate.

By reason of the supporting-frames being 75 formed oblong it will be observed that I secure three adjustments for the supplemental grate—namely, the lowest adjustment by means of setting the frames horizontally upon the grate of the stove—that is, the long sides 80 horizontal—the intermediate adjustment by setting them sidewise—that is, flat—the opposite edges being adjacent to the grates, and the highest adjustment by setting them endwise—that is, with the longitudinal sides vertically disposed so that the supplemental 85 grate is brought toward the top of the stove, and therefore designed for a smaller amount of fuel and for radiating a greater amount of heat than when set low down.

90

As one of the many means for adjusting the supplemental grate I may employ the suspension-rod 12, passed upwardly through the four corners of the grate-frame and through openings in the top of the stove, as 95 shown by dotted lines in Figs. 1 and 2, the ends of the rods above the top of the stove being provided with ordinary taps or adjusting-nuts 13, by which an adjustment is secured, as will be apparent. In this manner a 100 stove is especially adapted for use in summer and for the burning of such light fuel as wood, cobs soaked in oil, &c., and to radiate to the top of the stove the necessary heat for cook-

ing purposes without having a big bed of fire calculated to last long after the operation of cooking has been finished.

When the grate is employed for the burning of oil-soaked cobs, an imperforate pan 13 is used. This pan acts to shut off the draft and to catch and collect all drippings.

If desired, I also employ a pair of space-bolts 14, connecting the supporting-frames 10 with the fire back of the fire-box, and by the same I am enabled to force the supplemental grate snugly against the front wall of the fire-box and maintain the same in position.

Having described my invention, what I claim is—

1. The combination, with the supplemental grate-frame having bolt-openings, of oblong grate-supporting frames provided at their upper ends and side portions with bolt-holes 20 adapted to register with bolt-holes formed in the grate, and bolts for insertion in the holes, substantially as specified.

2. The herein-described grate attachment, consisting of an oblong frame, a series of

transverse grate-bars the extremities of which 25 are upwardly bent, and a series of short bars forming a continuation of the bent ends of the transverse bars and secured to the end bars of the grate-frame, substantially as specified.

3. The combination, with the fire-box, of a pair of supporting-frames, a grate mounted thereon, and a pair of spacing-bolts connecting the frames and fire back thereof, substantially as specified.

4. The combination, with the supplemental grate and means for supporting the same within a fire-box and above the grate thereof, of an imperforate pan mounted upon the supplemental grate, substantially as specified.

In testimony that I claim the foregoing as my own I have hereto affixed my signature in presence of two witnesses.

MOSES N. COLE.
